SLIPPER

Nancy J. Goodman, 147A W. Hilldale Blvd.,
San Mateo, Calif.

Filed Mar. 30, 1960, Ser. No. 59,947

Term of patent 14 years

(Cl. D7—7)

FIG. 1

FIG. 2

Figure 1 is a perspective view of a slipper showing my new design; and

Figure 2 is a front elevational view thereof. The side and back portions opposite those shown in Figs. 1 and 2 are of a similar texture and are substantially plain.

I claim:

The ornamental design for a slipper, as shown and described.
